UNITED STATES PATENT OFFICE.

JOEL CHENEY WELLS, OF SOUTHBRIDGE, MASSACHUSETTS.

DESIGN FOR A TAG.

SPECIFICATION forming part of Design No. 30,254, dated February 21, 1899.

Application filed January 23, 1899. Serial No. 703,180. Term of patent 7 years.

To all whom it may concern:

Be it known that I, JOEL CHENEY WELLS, a citizen of the United States, residing at Southbridge, in the county of Worcester and

5 State of Massachusetts, have invented and produced a new and original Design for Tags, of which the following is a specification, reference being had to the accompanying drawing, forming a part thereof.

10 My invention relates to tags; and it consists in a new and original design for tags, as will be hereinafter fully described.

The drawing is a plan view of a tag, showing my design.

15 My design for a tag consists of an enlarged end *a*, of circular shape, and the tapering stem *b*, extending out from one edge thereof, with the enlarged end *c* therein. In the body of the tag is a perforation *d*.

20 What I claim is—

The design for a tag, substantially as shown and described.

J. CHENEY WELLS.
